UNITED STATES PATENT OFFICE.

WILLIAM GOETZ, OF NOROTON HEIGHTS, CONNECTICUT.

TOY.

Application filed April 1, 1922. Serial No. 548,577.

To all whom it may concern:

Be it known that I, WILLIAM GOETZ, a citizen of the United States of America, residing at Noroton Heights, in the county of Fairfield and State of Connecticut, have invented certain new and useful Improvements in Toys, of which the following is a specification.

This invention relates to toys and more particularly to that type of toy known as spinning tops, and has as its object to provide a top having a handle by which it can be conveniently manipulated prior to its release.

15 A further object is in the provision of a resilient point causing a peculiar bounding movement of the top when discharged from its holder.

Another purpose is to provide means for 20 engaging the operating cord in a quick and effective manner.

These objects are secured by the novel construction and combination of parts hereinafter described and shown in the accompanying drawing, forming a material part 25 of this disclosure and in which:—

Figure 1 is a top plan view of an embodiment of the top as engaged in its holder.

Figure 2 is a side elevational view of the 30 same.

Figure 3 is a transverse sectional view taken on line 3—3 of Figure 2.

Figure 4 is a fragmentary sectional view taken on line 4—4 of Figure 1.

35 In the drawing, the numeral 10 designates a solid spherical knob constituting the upper element of the top, the same having a flat, beaded base portion 11 from which extends a conical stem 12, presenting a surface on which is wound the cord 13.

40 A recess 14 is formed in the periphery of the stem 12, midway in its length and leading from the recess is a narrow slot 15 curved to blend at its end with the stem, as shown best in Figure 3.

45 Said recess is adapted to receive a knot or the like at the end of the cord 13, acting to hold the cord in engagement while it is being wound but becomes released as the cord is pulled from the stem.

The lower end of the stem is provided 50 with a metal ferrule 16 and contains an axial recess 17, in which is slidably mounted a plunger 18 having a rounded outer end and a bar 19 extending into the stem.

55 Said plunger is held normally outward

by a coiled compression spring 20 in the recess and a pin 21 passes transversely through the bar 19, the ends of the pin moving in an elongated slot 22 which limits the 60 movement of the plunger 18 as well as prevents it from leaving the recess 17.

A handle having opposed ends 23 of any convenient length and proportioned to be easily held, has a central enlarged portion 65 24 containing a through opening 25 adapted to receive the stem 12 together with the cord wound upon it.

Extending transversely through the sides of the enlargement 24, in register with the 70 axis of the opening 25, are circular holes 26 from which extend diagonal passages 27 leading to the upper side of the handle, said 75 passages being arranged in opposed relation.

In operation, the knot or terminal of the 75 cord is engaged in the recess 14, passed through the slot 15 and then maneuvered to enter one of the passages 27, finally seating the cord in the hole 26.

The top is then entered, stem downward 80 thru the opening 25 and by grasping the knob the top will be turned, winding the cord on its periphery.

Thereupon a sharp pull on the free end 85 of the cord will cause the top to rise out of the opening, due to the inclined passages 27, become free from the handle and alight on any convenient surface, presenting the spring pressed plunger point downward, cushioning the fall of the top, at that time 90 rapidly rotating and causing it to hop in a manner not possible with ordinary spinning tops.

Obviously the momentum gained by the 95 head 10 will cause the top to continue to rotate a considerable period of time.

Having thus described my invention, what I claim as new and desire to secure by Letters Patent, is:—

A spinning top comprising a spherical 100 knob, a conical stem depending therefrom, a ferrule secured about the lower portion of said stem, a tip pin slidable axially in said stem, said pin having a reduced portion, reaching into the body of said stem, a 105 spring encircling the reduced portion normally projecting the pin outwardly of the stem, means for limiting the relative movement of said pin and stem, and means for spinning the top.

In witness whereof I affix my signature.

WILLIAM GOETZ.
